STOCKING

Paul R. Nestler, Green Lane, Pa.

Application May 23, 1952, Serial No. 19,847

Term of patent 14 years

(Cl. D47—7)

To all whom it may concern:

Be it known that I, Paul R. Nestler, a citizen of the United States, residing at Green Lane, Pennsylvania, have invented a new, original, and ornamental Design for a Stocking, of which the following is a specification, reference being had to the accompanying drawing, forming a part hereof.

Fig. 1 is a side perspective view of a stocking showing my new design; and

Fig. 2 is a fragmentary rear perspective view of the stocking shown in Fig. 1.

I claim:

The ornamental design for a stocking, as shown.

PAUL R. NESTLER.
